UNITED STATES PATENT OFFICE.

FREDERICK E. GOLDSMITH, OF HAMILTON, OHIO, ASSIGNOR, BY MESNE ASSIGNMENTS, TO THE CERAMIC MACHINERY COMPANY, OF HAMILTON, OHIO.

TILE-COATING MACHINE.

No. 826,182.

Specification of Letters Patent. Patented June 29, 1909.

Application filed May 1, 1903, Serial No. 155,115. Renewed May 31, 1904. Serial No. 210,579.

To all whom it may concern:

Be it known that I, FREDERICK E. GOLDSMITH, a citizen of the United States, residing in Hamilton, Butler county, Ohio, have invented certain new and useful Improvements in Tile-Coating Machines, of which the following is a specification.

This invention relates to machines for coating tile and the like with the liquid material which subsequently forms the glaze when the tile are fired. The desirability of employing machinery for this work is very great, both from an economic and humanitarian standpoint. As at present practiced, in this country and abroad as well, the coating of tile is all done by hand, and usually by sprinkling the coating liquid over the tile or by dipping the tile into a body of the liquid. In either case the process is slow and 20 the labor costs high, while the results are so defective that a large percentage of the product is of an inferior grade. In both cases, also, the process employed results in a partial coating of the edges as well as the 25 faces of the tile, and this not only involves a waste of the coating material, which is expensive, but renders it necessary that the edges of the tile thus coated should be scraped off in a subsequent operation and at 30 a considerable additional cost. Moreover, both of these processes necessitate the dipping of the hands into the coating material, and as the latter is of a poisonous nature, usually a lead compotind, the operatives become diseased and can work at the trade only for short periods at a time. And this is particularly true with children, who are at present largely employed on this work in tile manufacturing establishments.

I have devised mechanism for coating ceramic articles such as tile, brick, etc., which does away with hand labor and produces better results than have heretofore been attained.

Broadly considered, my invention comprises a coating device, a conveyer for moving the objects to be coated across the coating device, a reservoir for coating material, means for agitating and keeping in proper condition the material in the reservoir and means for supplying coating material from the reservoir to the coating device. In addition, the mechanism is frequently arranged so that coating material is circulated from the reservoir to the coating de-

vice in excess of the amount required for deposition upon the objects. The excess may be arranged to return to the reservoir from the coating device.

A particular machine constituting one of the embodiments of the invention may be described in general terms as follows: The coating device is a roll which dips into a shallow pool of coating material that is constantly renewed from an actively agitated body or mass of such material constituting a main source of supply. A most satisfactory means of providing such a shallow pool of active and constantly agitated coating material, I have found to consist in a continuous or endless surfaced dipping member, preferably a large roll or drum, mounted to dip and rotate in the main body of coating material and arranged in conjunction with a dam or abutment extending across the face of the drum, and forming a curved spout contiguous to the coating roll, through which the coating material passes, the spout terminating in a somewhat restricted opening or discharge slot, from which the coating material is projected with more or less velocity upon the face of said roll at varying heights, depending upon the adjustment of the spout and slot effected by movement of the dam. This dam intercepts the film of material carried up by the drum, and causes it to pile up in a shallow pool beneath the coating roll, which is arranged to rotate in close proximity to but out of contact with the drum, just behind the dam or on that side of the dam from which the coating material approaches. With this construction the dipping drum acts, in effect, as a pump to keep the pool replenished with freshly mixed coating material of practically uniform consistency, and the coating roll, rotating through this pool has its surface continuously supplied with this perfectly mixed material, ready to be applied to the tile. The agitation of the main body of coating material may in this case be accomplished by the dipping member or drum itself, which, to this end, will be arranged to dip into such material nearly to the bottom of the tank or vat in which the material is provided, and may, as a further improvement, be provided with suitable vanes or arms for more completely stirring up the material as the drum rotates. All of which, together with various other features of improvement,

will be fully understood from the following detailed description of a tile coating machine constructed in accordance with my invention in one of the forms in which may be practically embodied and illustrated in the accompanying drawings, in which:—

Figure 1 is a side elevation of the machine provided with my improvements. Fig. 2 is an opposite side elevation thereof. Fig. 3 is a top plan view. Fig. 4 is a vertical longitudinal section taken on line *b* of Figs. 3 and 6. Fig. 5 is an enlarged detail of the coating roll and adjacent parts of the machine. Fig. 6 is a vertical transverse section of the machine taken on line *a* of Figs. 1, 2 and 4. Fig. 7 is a perspective view of one of the agitator blades.

In said drawings, 1 designates a vat for containing the liquid coating material, and 20 3 a drum or wheel mounted to rotate within the vat and dipping nearly to the bottom thereof. Just above the drum 3 is a coating roll 22, the periphery of which rotates in proximity to the periphery of the drum 3, 25 but does not come quite in contact with it.

Extending across the face of the dipping drum 3, at a point adjacent to the lower portion of the coating roll 22, is a dam or abutment 20 which intercepts the film or layer 30 of coating material that clings to the rising surface of the drum, and causes it to pile up beneath the coating roll in a sort of shallow pool, into which the coating roll dips. The drum thus serves, as it were, as a pump 35 to constantly supply fresh material to this pool and thence to the coating roll, and for this purpose may, if desired, be provided with a covering 4, of finely corrugated rubber, or the like, as shown. This dam 20 is 40 herein shown as made in the form of a concave blade or scraper, although it may be of any other suitable shape or construction, and is adjustably mounted so that its lower edge can be moved closer to or farther from 45 the surface of the drum, or advanced or retracted with respect to the coating roll. By the same means the discharge slot between the upper edge of the dam and the coating roll is varied as to its capacity and 50 elevation in relation to the axis of the coating roll. It will be evident that coating material is introduced to the spout between the lower edge of the dam and the coating roll at a considerable velocity (depending upon 55 the speed of the drum 3), and by reason of its momentum and decreasing size of the spout. And by movement of the coating roll, the coating material is ejected through the slot with more or less force upon the 60 surface of the coating roll. It is also apparent that by adjustment of the dam horizontally and vertically the elevation at which the coating material is finally delivered to 65 the coating roll may be varied as desired to meet varying conditions imposed by the

character of the coating material employed, the nature of the biscuit to be coated, etc. To this end the dam is conveniently made as a part of a generally rectangular frame work 18, which surrounds the lower portion 70 of the coating roll, and sets loosely down into an aperture 17 in a supporting plate 14 that also acts as a cover plate for the middle portion of the vat. A screw and slot connection 19 between the plate 14 and frame 75 18, enables this frame and the dam to be adjusted horizontally within the aperture 17, while adjusting screws 16, at one end of the plate 14, enables the entire plate, with the frame and dam, to be adjusted vertically, the other end of the plate being secured over studs 15 which permit of its 80 tilting sufficiently for the purpose of this adjustment.

While the principal object of the dipping drum 3 is to raise the coating material to the coating roll, as before stated, it is also utilized, in this instance, as a means for constantly agitating the body of such material within the vat, and with a view of 85 intensifying this action, may be provided with stirring devices, such as cups 7 and blades 8, which devices are herein shown as interchangeably inserted in dovetailed sockets 6 formed on the interior of the rim 90 of the drum. The cups 7, as the drum revolves, will become filled with liquid from the vat as they pass through it, and will empty it back into the vat again, as they are raised above the surface of the material 100 in the complete rotation of the drum. The blades 8 are shown as projecting outwardly from the rim of the drum, and are provided with oblique flanges 9 which tend to urge the material inwardly from the wall of the 105 vat toward the drum as the latter revolves, and in this manner aid in its constant agitation. The relative number of cups and 110 blades used, will depend upon the character of the particular material in the vat, and 115 may be obviously varied as desired, the effect of the agitation being in all cases to keep the material actively stirred up and of uniform consistency throughout and at its surface as well as at the bottom of the vat. The withholding of the coating roll from 120 actual contact with the dipping drum, also enables the surface velocities of these members to be independently regulated, and ordinarily that of the drum, in view of its agitating function, will be much faster than that of the coating roll. These relative velocities will, however, be required to be varied according to the particular nature of the coating material used, and according 125 to atmospheric and other changeable conditions.

As herein shown, the machine is arranged to be driven by a driving cone 5 on the end of the shaft 2 of the dipping drum, which 130

shaft, to this end, is extended through a stuffing box in the side of the vat. A cone 29 is also provided on the shaft 2 and is arranged to be belted to a corresponding cone 29 on a countershaft 28. This countershaft carries a gear 30 which intermeshes with a gear 31 on the shaft of the coating roll 22, and thus drives the coating roll with a greater or less speed relative to the speed of 10 the dipping drum, according to the manner in which the belt is adjusted on the cones 29. The actual surface velocity of the coating roll will also be adjusted by these driving means with reference to the character and 15 consistency of the coating material, in such manner as to apply the material to the tile at a rate productive of the best results. The tile may be passed over the coating roll by hand, but will advantageously be fed to and 20 from it by two carrier mechanisms, such as the endless belts 25 and 27, one arranged to travel toward and the other away from the roll. The belt 25 serves as a feeding-table for convenience in supplying tile to the coating 25 roll. The upper surfaces of these carrier belts are preferably arranged slightly below the top of the roll so that the weight of the tile rests upon the roll in passing over it, and tends to bring it sufficiently in contact with the roll to properly receive the 30 coating material. With some coating materials and styles of tile, however, some pressure in addition to the weight of the tile is desirable, and this may be conveniently afforded, when necessary by a pressure roller 35 of any suitable character, herein shown as a gravity roller mounted in bearings 34 which slide vertically in guides 21, just above the coating roll.

40 To drive the aprons 25 and 27 the shafts of the rollers 23, around which their proximate ends are carried, are shown as provided with pinions 33, of which one intermeshes with the gear 30 on the shaft 28, while the other intermeshes with an idler 32 that intermeshes with and is driven by the pinion 31 of the coating roll. This gearing is so proportioned as to drive the bearing off apron 27 somewhat more rapidly than the feeding 45 apron 25, in order to insure that the tile will be carried away at least as rapidly as they are fed to the coating roll. The bearings for these apron rollers 23, and also for the rollers 24, around which the aprons are 50 carried at their outer ends, are shown as mounted on plates 10 and 12 which cover the ends of the vat beyond the middle cover plate 14, the outer bearings being adjustable so that the tension of the aprons may be 55 regulated as desired. These cover plates 10 and 12 are shown as hinged to the vat at 11 and 13, respectively, and may be thrown back to give access to the vat.

60 In the operation of the machine, the tile are placed, face downward, upon the feeding

in apron or table 25, and are thereby delivered to the coating roll, over which they pass to the bearing off apron 27 that discharges them from the machine. As the tile pass over the coating roll they become uniformly 70 surfaced with the coating material, which, owing to their very absorbent nature, is instantly picked up or absorbed from the roll, and immediately becomes sufficiently dry and firm to permit of the subsequent contact 75 of the coated surface of the tile with the bearing off apron without injury. The projection of the top of the coating roll slightly above the upper surface of the aprons causes the tile to contact uniformly with the roll, 80 even if slightly warped or curved, and to rest upon it with sufficient pressure, reinforced, when necessary, by the pressure roll. With a suitable covering for the coating 85 roll, such as wire gauze, the film of coating material to which the tile is exposed is very shallow, and does not lap over upon the edge of the tile so as to require subsequent removal, and at no point in the entire operation is it necessary for the person running 90 the machine to come in contact with the tile or coating material.

It will be understood that wide changes may be made in the construction of the tile coating machine thus described, without departure from the broad spirit of the invention claimed, and that the word "tile", as employed throughout this specification, is intended to include, generically, any sort of 95 bricks or blocks to which a glazing coating 100 is to be applied.

In operation the rotary pump or drum raises the coating and delivers it in a continuous stream from the contents of the tank upon the face of the coating roll including the upper portion thereof. At the same time the agitator upon the rotary drum or pump is continuously mixing the contents of the tank.

Reference is hereby made to applicant's co-pending applications Serial Number 203,609, filed Apr. 18, 1904, for tile coating machinery; Serial Number 223,071, filed Sept. 2, 1904, for agitator; Serial Number 253,720, filed Apr. 3, 1905, for coating machine; Serial Number 257,370, filed Apr. 25, 1905, for process of coating tiles.

I claim as my invention:—

1. The combination with a coating roll, of movable transmitting means for discharging coating material from the vat into a pool beneath the roll into which the latter dips, substantially as described.

2. The combination with a coating roll, of a dam in proximity to the lower portion of said roll, and movable transmitting means for discharging coating material from the vat against the dam to form a pool into which the roll dips, substantially as described.

3. The combination with a coating roll, of
movable transmitting means for discharging
coating material from the vat into a pool
beneath the roll into which the latter dips,
and means for conveying tile over said coat-
ing roll, substantially as described. 70
4. The combination with a coating roll, of
a dam in proximity to the lower portion of
said roll, movable transmitting means for
discharging coating material from the vat
against the dam to form a pool into which
the roll dips, and means for conveying tile
over said coating roll, substantially as de-
scribed. 75
- 15 5. The combination with a vat for the
coating material, of a drum running in the
vat, a coating roll arranged in proximity to
the drum, and a dam arranged in proximity
to the drum and coating roll, and against
20 which coating material is discharged to form
a pool into which the roll dips, substantially
as described. 80
- 25 6. The combination with a vat for the
coating material, of a drum running in the
vat, a coating roll arranged in proximity to
the drum, a dam arranged in proximity to
the drum and coating roll, and against
30 which coating material is discharged to
form a pool into which the roll dips, and
means for conveying tile over said coating
roll, substantially as described. 85
- 35 7. The combination with a vat for the
coating material, of a drum running in the
vat, a coating roll arranged in proximity to
the drum and receiving coating material therefrom,
40 to but out of contact with the drum and re-
ceiving coating material therefrom, a dam
in proximity to the drum and roll and means
for independently varying the surface veloci-
ties of the drum and roll, substantially as
45 described. 90
- 45 8. The combination with a vat for the
coating material, of a drum running in the
vat, a coating roll arranged in proximity
to but out of contact with the drum and re-
ceiving coating material therefrom, means
50 for independently varying the surface ve-
locities of the drum and roll, and means for
conveying tile over said coating roll, sub-
stantially as described. 95
- 50 9. The combination with a vat for the
coating material, of a drum running in the
vat, a coating roll arranged in proximity to
the drum, a dam arranged in proximity to
55 the drum and coating roll, and against
which coating material is discharged to form
a pool into which the roll dips, and means
for independently varying the surface ve-
locities of the drum and roll, substantially
60 as described. 100
- 60 10. The combination with a vat for the
coating material, of a drum running in the
vat, a coating roll arranged in proximity to
the drum, a dam arranged in proximity to
65 the drum and coating roll, and against
which coating material is discharged to form
a pool into which the roll dips, means for
conveying tile over said coating roll, and
means for independently varying the surface
velocities of the drum and roll, substantially
as described. 105
11. The combination with a vat for the
coating material, of a coating roll, and mov-
able transmitting means for agitating the
coating material within the vat and dis-
charging it into a pool beneath the coating
roll, substantially as described. 110
12. The combination with a coating roll,
of a dam in proximity to the lower portion
of said roll, and movable transmitting
means for agitating the coating material
within the vat and discharging it against
the dam to form a pool into which the roll
dips, substantially as described. 115
13. In a tile coating machine, the com-
bination, substantially as set forth, of a vat
for the coating material, a drum mounted
therein on a horizontal axis, mechanism dis-
posed within the vat and working below and
above the surface of the coating material
therein for agitating the coating material,
a coating roller disposed across but free from
the upper portion of the face of the drum
and receiving coating material therefrom,
and mechanism for conveying tiles over said
coating roller. 120
14. In a tile coating machine, the com-
bination, substantially as set forth, of a vat
for the coating material, a drum mounted
therein on a horizontal axis and provided
with a non-metallic jacket, mechanism dis-
posed within the vat and working below and
above the surface of the coating material
therein for agitating the coating material,
a coating roller disposed across the upper
portion of the face of the drum and receiv-
ing coating material therefrom, and mech-
anism for conveying tiles over said coating
roller. 125
15. In a tile coating machine, the com-
bination, substantially as set forth, of a vat
for the coating material, a drum mounted
therein on a horizontal axis, mechanism
mounted upon the drum within the vat and
working below and above the surface of the
coating material therein for agitating the
coating material, a coating roller disposed
across but free from the upper portion of
the face of the drum and receiving coating
material therefrom, and mechanism for con-
veying tiles over said coating roller. 130
16. In a tile coating machine, the com-
bination, substantially as set forth, of a vat
for the coating material, a drum mounted
therein on a horizontal axis, cups mounted on
the drum, a coating roller disposed across the
upper portion of the face of the drum and
receiving coating material therefrom, and
mechanism for conveying tiles over said coat-
ing roller. 135
17. In a tile coating machine, the combina-

tion, substantially as set forth, of a vat for the coating material, a drum mounted therein on a horizontal axis, agitator blades mounted on the drum and projecting toward the side walls of the vat, a coating roller disposed across but free from the upper portion of the face of the drum and receiving coating material therefrom, and mechanism for conveying tiles over said roller.

10 18. In a tile coating machine, the combination, substantially as set forth, of a vat for the coating material, a drum mounted therein on a horizontal axis, agitator blades mounted on the drum and projecting toward the side walls of the vat, gathering flanges on said blades to urge the coating material from the vat-walls toward the drum, a coating roller disposed across the upper portion of the face of the drum and receiving coating material therefrom, and mechanism for conveying tiles over said coating roller.

15 19. In a tile coating machine, the combination, substantially as set forth, of a vat for the coating material, a drum mounted therein on a horizontal axis and provided with sockets at the sides of its rim, devices secured in said sockets for agitating the coating material as the drum rotates, a coating roller disposed across the upper portion of the face of the drum and receiving coating material therefrom, and mechanism for conveying tiles over said coating roller.

20 20. In a tile coating machine, the combination, substantially as set forth, of a vat for the coating material, a drum mounted therein on a horizontal axis, mechanism disposed within the vat and working below and above the surface of the coating material therein for agitating the coating material, a coating roller disposed across but free from the upper portion of the face of the drum and receiving coating material therefrom, and aprons at the front and the rear of said coating roller to convey tiles over said roller.

25 21. In a tile coating machine, the combination, substantially as set forth, of a vat for the coating material, a drum mounted therein on a horizontal axis, mechanism disposed within the vat for agitating the coating material therein, a coating roller disposed across the upper portion of the face of the drum and receiving coating material therefrom, and aprons at the front and the rear of said coating roller to convey tiles over said roller, the carrying surface of said aprons being below the level of the top of the coating roller.

30 22. In a tile coating machine, the combination, substantially as set forth, of a vat for the coating material, a drum mounted therein on a horizontal axis, mechanism disposed within the vat for agitating the coating material therein, a coating roller disposed across the upper portion of the face of the drum and receiving coating material

therefrom, hinged lids for the vat at the front and the rear of the coating roller, and aprons mounted on said lids.

23. In a tile coating machine, the combination, substantially as set forth, of a vat for the coating material, a drum mounted therein on a horizontal axis, mechanism disposed within the vat for agitating the coating material therein, a coating roller disposed across the upper portion of the face of the drum and receiving coating material therefrom, hinged lids for the vat at the front and the rear of the coating roller, aprons mounted on said lids, and means for vertically adjusting the edges of said lids contiguous to the coating roller.

28. In a tile coating machine, the combination, substantially as set forth, of a pair of endless aprons with their upper surfaces disposed in substantially the same horizontal plane, apron rollers for the support and actuation of said aprons, a coating roller disposed in the gap between the contiguous ends of the two aprons and having its upper surface higher than the upper surfaces of the aprons and arranged to have tiles carried over it by the action of the two aprons, and means for continuously supplying the periphery of the coating roller with coating material.

25. The combination of a coating surface, a dam in proximity thereto and movable transmitting means for supplying coating to the dam.

26. The combination of a dam forming a coating pool, a coating surface dipping therein and movable transmitting means for supplying coating to the dam.

27. The combination with a tank, an agitator movable therein, a rotative cylinder mounted across the top of the tank, a pressure-roll mounted over the cylinder, a feeding-table leading toward and a delivery-apron leading from the top of the cylinder, of a pump arranged to deliver in a continuous stream the contents of the tank upon the face of the cylinder.

28. In combination, a tank, a rotative cylinder with an elastic face, and a pump arranged to deliver the liquid contents of the tank on the upper portion of the face of the cylinder.

29. The combination with a tank, a rotative cylinder mounted thereon, a pressure-roll mounted thereover, and a feeding-table, of adjustable means to deliver the contents of the tank in a continuous stream at different elevations upon the face of the cylinder.

30. The combination of a tank, a cylinder having an elastic face and mounted in fixed bearings to rotate in a vertical plane, a vertically-adjustable spout communicating with the tank and formed with a discharge-slot adjacent to, and parallel with, the cylinder, whereby the contents of the tank may dis-

charge on the cylinder at different elevations.

31. In combination, a rotative cylinder, a feeding-table, a tank, an agitator therein, and adjustable means arranged to deliver the liquid contents of the tank at different elevations on the face of the cylinder.

32. The combination of a coating reservoir, an agitator within the reservoir, a coating device, a pump for supplying coating material from the reservoir to the coating device and means for moving objects to be coated across the coating device.

33. The combination of a reservoir for coating material, an agitator within the reservoir, a coating device, means intermediate the reservoir and the coating device for circulating coating material from one to the other, and means for conveying objects to be coated across the coating device so that coating is applied to their lower surfaces.

34. The combination of a reservoir for coating material, an agitator moving within the reservoir, a coating device constructed and arranged to deliver coating material at substantially its upper surface, means for moving objects to be coated across the coating device in substantially a horizontal plane and means for circulating coating material from the reservoir to the coating device in excess of the amount actually required for deposition upon the objects.

35. The combination of a coating reservoir, an agitator moving within the reservoir, a coating device for applying coating material to ceramic objects, means for moving objects to be coated to the coating device so that they receive coating material on their lower surfaces and a pump for con-

veying coating material from the reservoir to the coating device in excess of the amount actually required.

36. The combination of a coating-receptacle, a coating surface, transmitting means for supplying coating from the receptacle to the coating surface, a movable cover for the receptacle, and a conveyer mounted upon the cover.

37. In coating apparatus, the combination of a frame, a coating device thereon, a feed belt, a delivery belt, and a support for one of the belts hinged to the frame.

38. In coating apparatus, the combination of a frame, a coating receptacle, a coating device above the receptacle, a support hinged to the frame and feed and delivery belts for the coating device, one of said belts being mounted on said support.

39. In coating apparatus, the combination of a frame, a coating receptacle, a coating device above the receptacle, a cover hinged near one end of the frame so that its free end is adjacent to the coating device and an endless belt carried by the cover.

40. In an apparatus for coating, the combination of a frame, a coating receptacle, a coating device above the receptacle, a lid hinged to the frame at one side of the coating device with its free end adjacent to said device, another lid hinged to the frame at the other side of the coating device with its free end adjacent to said device and feed and delivery belts, one carried by each of said lids.

FREDERICK E. GOLDSMITH.
